UNITED STATES PATENT OFFICE

FRENCH H. MOREHEAD, OF BOSTON, MASSACHUSETTS

METHOD AND APPARATUS FOR MAKING SAND CORES

Application filed February 8, 1928. Serial No. 252,770.

My present invention relates to methods and apparatus for making sand cores for casting tubular articles such as pipe, hydrant barrels, columns and the like of the type referred to in my co-pending application Serial No. 252,771, filed February 8, 1928.

As is well known to those skilled in the art, cores for long articles cast in substantially horizontal position are bent or distorted during casting by the pressure of the molten metal which tends to float the core. Attempts have been made to counteract this effect as for instance by subjecting the core after it is in place in the mold to stresses which tend to bend the core in the direction opposite to that produced by its tendency to float. The tendency of the core to float and thus be distorted can also be overcome by employing a core which is bent the right amount during its manufacture so that when the metal is poured the tendency to float brings it to the desired straight position. My present invention, therefore, has for its object a method and apparatus for making suitable bent cores rapidly and economically.

It is the object of the invention to produce by rotation cores adapted to overcome the above mentioned difficulties and which may be straight but not of circular cross section or to produce bent cores which may or may not be of circular cross section, any of which may be uniform or variable in cross section from end to end. In the practice of my invention, suitable core sand is deposited on a rotating arbor and is trimmed by a suitable knife as it rotates, either the arbor, or the knife or both being moved and preferably flexed in time with the rotation of the arbor. In practice I prefer to bend the knife, but I do not limit myself to this specific form, and intend to claim my invention broadly since as already stated the same or equivalent results can be obtained by bending the arbor or giving the knife and arbor proper relative movements.

The apparatus embodying my invention is simple and effective and will produce suitable cores as fast as apparatus which produces straight cores, and the cores so produced can be employed in ordinary molds

without employing any means to bend them after they are placed in the mold or to hold them against bending due to their tendency to float in the molten metal; therefore, casting with cores made in accordance with the process embodying my invention is much simplified and cheapened. Tubular articles produced by the use of the cores so made have a uniform cross-section and therefore metal is saved. The number of defective articles which must be rejected is reduced and the articles have a longer life, all with no additional expense in manufacture.

Before explaining in detail the present invention, and the method or mode of operation embodied therein, it is to be understood that the invention is not limited in its application to the details of construction and arrangement of parts illustrated in the accompanying drawings since the invention is capable of other embodiments and of being practiced or carried out in various ways. Also it is to be understood that the phraseology or terminology employed herein is for the purpose of description and not of limitation, and it is not intended to limit the invention beyond the terms of the several claims here-to appended or the requirements of the prior art.

The invention will be more clearly understood from the following description in conjunction with the accompanying drawings; in which

Fig. 1 is an elevational view partly in section of one type of apparatus for producing the specially shaped core;

Fig. 2 is a plan view taken upon the line 2-2 of Fig. 1;

Fig. 3 is a similar view of the apparatus with a different type of arbor;

Fig. 4 is an end elevational view, partly broken away, of another type of apparatus for producing the core;

Fig. 5 is a side elevational view of the same, and

Fig. 6 is a sectional view taken upon the line 6-6 of Fig. 5.

Referring to the drawings, the apparatus comprises (Figs. 1, 2 and 3) a support 10 carrying a suitable frame 11 in which an arbor

14 is rotatably mounted. The arbor 14 may be in the form of a hollow pipe provided near each end with grooves 15 forming bearing surfaces for rolls 16 fixed upon shafts 17 suitably mounted for rotation in bearings 18 in the frame 11.

The arbor 14 may be rotated by mechanism at each end thereof including a shaft 20 rotatably mounted in suitably bearings 21 in the frame and provided at one end with a spline or key 23 adapted to engage a keyway 24 in the ends of the arbor. The shafts 20 may be rotated in synchronism and for this purpose each is provided with a gear 25 operatively connected with a gear 22 on a shaft 9 rotatably mounted in the frame. A pulley or sprocket wheel 8 is secured upon one of the shafts 20 and may be driven from any suitable source of power to rotate the shafts 20 and arbor in synchronism.

The frame 11 is provided with suitable lugs 26 extending toward the arbor 14 and upon which a knife 27 capable of being flexed is mounted. The knife 27 is provided with suitable openings 28 each adapted to receive a suitable fastening device, such as a screw 29, engaging one of the lugs 26. In order to compensate for the usual wear of the apparatus, a spring 30 is interposed between the frame 11 and the rear edge of the knife.

A suitable arrangement is provided for flexing the knife and may comprise a stirrup 33 having rearwardly and forwardly extending supports 34 and 35 movably mounted in suitable bearings 36 in lugs 37 and 38 extending upwardly from the frame 11. The knife 27 may be suitably secured to the forwardly extending support 35, as by screws 39. An eccentric or cam 40 is secured upon one end of a shaft 41 rotatably mounted in suitable bearings 42 in the frame, and is arranged for operative engagement with the stirrup 33. The cam 40 may be actuated in any suitable manner in timed relation with the rotation of the arbor, and for this purpose a driving gear 44 is mounted on the shaft 20 and is operatively connected with a gear 45 secured on the shaft 41 by an idler gear 46 secured upon a shaft 47 rotatably mounted in the frame 11.

The arbor 14 may be of any suitable shape depending upon the type and shape of core which is to be produced. The types of arbors illustrated are adapted for use in the production of cores employed for making pipes. This arbor may be of cylindrical form, as shown in Fig. 3, or it may be provided with an abnormal bend, as shown in Fig. 2, substantially equal to the bend desired to be produced in the finished core. In any case the arbor should be provided with suitable openings 48 to permit escape of gases formed by contact of the molten metal with the sand core.

A suitable hopper 50 is supported in any convenient manner, as by a frame 51, above

the arbor 14 and is provided at its lower end with a chute 52 extending to a point close to the arbor. A riddle 53 is suspended within the hopper and is provided with upwardly extending arms 54 pivotally mounted upon shafts 56 secured in the frame 57 extending upwardly from the hopper.

In the manufacture of cores, power is supplied to rotate the arbor 14 and flex the knife 27 in timed relation. The desired flexure of the knife may be produced by selecting a suitably shaped cam or eccentric 40. A suitable mixture of sand and binder is introduced into the riddle 53 and the latter is vibrated, whereupon the sand and binder mixture passes downwardly through the hopper 50 and chute 52 and is deposited upon the arbor 14 with considerable impact. The sand will cling to the surface of the arbor due to the presence of the binder admixed therewith and will build upon the arbor until a sufficient amount has accumulated to engage the effective edge of the shaping knife 27. The knife will shear off any excess of sand and binder mixture and shape the same to the form of the core desired. The supply of sand and binder is then cut off and the arbor is rotated through one or two revolutions thereafter.

In Figs. 4, 5 and 6 I have shown a type of apparatus for making a crooked core by flexing or bending the arbor during its rotation. As illustrated, in this form of apparatus the knife is held stationary with its edge straight. This apparatus comprises a suitable support 60 having a frame 61 extending upwardly near each end of the apparatus for rotatably supporting rolls 62 upon which the normally straight arbor 63 rests. A cross member 64 in which a roll 65 is rotatably mounted is pivoted at one end to the frame 61 and detachably secured thereto, as by a bolt 66 and nut 67, at its other end, the arrangement being such as to bring the roll 65 into engagement with the arbor and hold the same against the rolls 62 during its rotation. The arbor 63 is provided with a groove 68 near each end thereof for engagement with the rolls 62 and 65.

An outer frame 70 extends upwardly from the support 60 and is spaced from each frame 61 and is provided at its top with a cross member 71 having a portion 72 forming part of a journal for an eccentric or cam 73 detachably mounted upon the arbor in any suitable manner, as by a set screw 74. A cross member is pivotally mounted at one side of the top of each frame 70 and is detachably secured to the other side as by a nut 75 and bolt 76. A shaping knife 77 is secured, as by screws 78, to a cross member 79 connecting frames 61.

The arbor may be rotated by mechanism at each end including a shaft 80 provided at one end with a spline or key 81 adapted to engage a slot or keyway 82 in the ends of the

arbor. The other end of the shaft 80 is connected by a universal joint 83 to a shaft 84 rotatably mounted in the frame. The driving mechanism at each end of the arbor may be connected to operate in synchronism. For this purpose each shaft 84 may be provided with a gear 85 operatively connected with a gear 86 near each end of a shaft 87 rotatably mounted in the frame. This mechanism may be operated from any suitable source of power transmitted for example to a pulley 88 mounted upon the shaft 84.

In operation of the apparatus shown in Figs. 4, 5 and 6 a suitable mixture of sand and binder is deposited upon the rotating arbor through a chute 90 from a hopper of the general type previously described. During rotation the eccentrics 73 will cause flexure or bending of the arbor 63 and the sand mixture 91 accumulated upon the arbor will be shaped by the knife 77 to cylindrical form. The amount of flexure of the arbor will be controlled by the character of the eccentrics 73. When the flexed arbor having the cylindrical body of sand mixture thereon is removed from the apparatus it will tend to straighten and thereby impart a curvature to the accumulated sand mixture 91 to provide a crooked core.

I claim:

1. The method of making a core which comprises depositing a suitable sand mixture on a revolving arbor, and shaping the sand mixture thereon by contact with a knife, said knife and said arbor being moved relatively towards and away from one another during the rotation of the arbor in such a way as to vary the distance between the arbor and the knife different amounts at different points longitudinally of the arbor.

2. The method of making a core which comprises depositing a suitable sand mixture on a revolving arbor, shaping the mixture by a knife during the rotation of the arbor, and flexing one of said members relative to the other during the rotation of the arbor.

3. The method of making a core which comprises depositing a suitable sand mixture upon a revolving arbor, shaping said mixture by a knife during rotation of said arbor, and moving said knife towards and away from said arbor during the rotation of the arbor in such a way as to vary the distance between the arbor and the knife different amounts at different points longitudinally of the arbor.

4. The method of making a core which comprises depositing a suitable sand mixture upon a revolving arbor, shaping said mixture by a knife during rotation of said arbor, and flexing said knife relative to said arbor in timed relation with the rotation of the arbor.

5. In an apparatus for making sand cores, a rotatable arbor, means for depositing a suit-

able sand mixture upon the arbor, a knife for shaping said mixture, and a cam operating in timed relation with the rotation of the arbor and acting upon said knife to flex it in timed relation with the rotation of the arbor.

6. In an apparatus for making sand cores, a rotatable arbor, means for depositing a suitable sand mixture upon said arbor, a knife for shaping said mixture, a support for said knife, a stirrup connected with said knife, and a cam engaging said stirrup to flex said knife.

7. In an apparatus for making sand cores, a rotatable arbor, driving mechanism for rotating said arbor, means for depositing a sand and binder mixture upon said rotating arbor, a support for said knife, a cam operated mechanism for flexing said knife, and means actuated in timed relation with said driving mechanism for actuating said cam operated mechanism.

In testimony whereof I affix my signature.
